UNITED STATES PATENT OFFICE

103,213

DESIGN FOR A LAMP SHADE

William Burger, Jamaica, N. Y., assignor to East Side Metal Spinning & Stamping Corp., New York, N. Y.

Application January 6, 1937, Serial No. 66,915

Term of patent 7 years

To all whom it may concern:

Be it known that I, William Burger, a citizen of the United States and a resident of Jamaica, county of Queens, State of New York, have invented a new, original, and ornamental Design for Lamp Shades, of which the following is a specification, reference being had to the accompanying drawing, forming part thereof, and in which:

Fig. 1 is a top view of the lamp shade showing my new design,

Fig. 2 is a side view, and

Fig. 3 an end view.

I claim:

The ornamental design for a lamp shade, as shown.

WILLIAM BURGER.
